FIRE ALARM BOX ATTACHMENT

Robert B. Long, Dayton, Ohio

Application April 23, 1932, Serial No. 607,116

5 Claims. (Cl. 177—379)

This invention relates to a fire alarm signal box, and more particularly to a removable hand cuff attachment for a fire alarm box.

An object of this invention is to provide such an attachment for fire alarm boxes that is operative in all weather conditions to determine who turned in the fire alarm.

Another object of this invention is to provide a device having a member or eaves for shedding water that permits the removal of a cuff irrespective of weather conditions.

Another object of this invention is to provide a device that is cheap, efficient, safe and dependable.

Further objects and advantages of the present invention will be apparent from the following description, reference being had to the accompanying drawings wherein a preferred embodiment of one form of the present invention is clearly shown.

In the drawings, Fig. 1 discloses a door of a fire alarm box. Fig. 2 discloses an attachment therefor. Fig. 3 is a rear view of a door for a fire alarm box. Fig. 4 is a fragmentary view showing the position of the movable parts disclosed in Fig. 3, in another position. Figs. 5 and 6 disclose fragmentary views of the attachment shown in Fig. 2. Fig. 7 is a transverse sectional view taken on the center line 7—7 of the disclosure shown in Fig. 2. Fig. 8 is a fragmentary sectional view taken on the line 8—8 in Fig. 3.

In the conventional fire alarm boxes there is found a fire alarm signal mechanism that is actuated by the reporter of the fire. In the accompanying drawings the signal mechanism includes the knob 10 rotatably mounted on a shaft 12 indirectly carried by the door 16 as more fully described later, and shielded by the cover 14 integral with the door, thus protecting the signaling mechanism from the elements. Instead of a knob, any other suitable signaling device may be used, such as a lever or a button supported in any suitable manner.

The fire alarm is turned in to the fire department by actuating the signaling mechanism. In the modification disclosed in the drawings, this is accomplished by turning the knob 10 that actuates lever 37 which may in turn actuate a mechanism, not shown, electrically or otherwise connected to the fire station.

The attachment 18, disclosed in Fig. 2, is a removable closure provided with an opening 20, and located in the opening below the cover. The closure 18 has a pair of gripping jaws 22 and 24, that are released by a suitable mechanism to be

described later, so as to grip the wrist of the operator as he turns the knob 10, whereby the person making the alarm carries the closure 18 on his wrist until the gripping jaws 22 and 24 are released, as will be described more fully later.

The shaft 12 is fixedly attached near one end of a lever 37 pivotally mounted on a stud 39 carried by the door. The cam 40 rotatably mounted upon the shaft 12 is connected to a sleeve 120 fixedly attached to the knob 10. This cam 40 engages a trigger 26 pivoted upon the stud 28 attached to the door and urged in a clockwise direction as viewed in Fig. 3, by a spring 30. This trigger 26 prevents the spring 32, having one hooked to the stud 34 and the other end hooked at 36 to a pawl 38, from rotating the pawl 38 about its pivot 140 until the trigger 26 is actuated in a counter-clockwise direction, as more fully described later.

When the sleeve 120 is rotated in a counter-clockwise direction as viewed in Fig. 3, spring 31, having one end hooked to cam 40 and the other end attached to member 38, urges cam 40 towards pin 33 carried by the door 16. When cam 40 is rotated so as to cause the pin 33 to register with the notch 35, the cam and shaft 12 will move downwardly causing member 37 to rotate in a clockwise direction about the pin 39 which actuates a suitable signaling system not disclosed, as the signaling system, per se, does not form any part of this invention. A pin 41 also carried by the door 16 provides a positive drive for causing a downward movement of cam 40 and member 37. The slot 43 in the door 16 permits up and down movement of the shaft 12 and the parts carried thereby.

When an alarm is turned in, the trigger 26 is actuated in a counter-clockwise direction by the cam 40, carried by the shaft 12, which causes the detent 42 to be moved in a counter-clockwise direction against the force of the spring 30, so as to clear the projection 44, permitting the pawl 38 to rotate in a counter-clockwise direction about the pivot 140 into the position disclosed in Fig. 4. The end 46 of the pawl 38 extends through a slot 112 in the door 16 and through a slot 48 in the upper member 50 of the attachment 18, and is normally seated in the bifurcated end 52 of the lever 54 pivoted at 56 as best seen in Fig. 5. The lever 54 is provided with a detent 58 and a shoulder 60 that engage the gripping jaws 22 and 24, and the pivotally mounted arms 66 and 68 respectively.

As the end 46 of the pawl 38 is rotated in a counter-clockwise direction as viewed in Fig. 3,

the lever 54 is moved in a counter-clockwise direction, as viewed in Fig. 5, permitting the gripper jaws 22 and 24 to advance toward each other and at the same time retract the pins 70 and 72 that are normally located in the pockets 74, shown in Fig. 1, permitting the door or closure 18 to drop out of position by rotating in a clockwise direction as viewed in Fig. 7 rotating about the stud 130. The pins 70 and 72 are normally urged to the out position by a spring 73 carried on a support 75 by a screw 77 and attached to members 66 and 68 by suitable screws.

The gripping jaws 22 and 24 pivotally mounted at 132 are urged into a closed position by a spring 76 gripping the wrist of the operator. The jaws 22 and 24 are held in this position by the dogs 78 and 80 pivoted at 82 and biased by a spring 84. The dogs 78 and 80 are shown in an operative position in full lines in Fig. 6, and in a released position in dotted lines.

A key 90, passing into the gripping jaw releasing mechanism 92 and rotated therein, causes member 94 to be rotated in a counter-clockwise direction into dotted position as viewed in Fig. 6, so as to engage the lever 96, pivotally mounted on 98 and carrying a pair of studs 100 and 102 that engage the ends 104 and 106 respectively of the dogs 78 and 80 so as to move these into the open position disclosed in dotted line position in Fig. 6, thereby permitting the gripper jaws 22 and 24 to be spread apart to release the hand.

When it is desirable to reinsert the closure or the cuff and after it has been released from the operator, the jaws 22 and 24 after being released by the key 90 are manually spread into open position disclosed in Fig. 6 which permits member 54 to rotate in a clockwise direction as viewed in Fig. 5. The detent 46 must also be moved from the dot-dash position disclosed in Fig. 3 to the full line position shown in the same figure. The closure may then be inserted into the opening in the box by first placing the pin 130 in its aperture and then rotating the cuff in a counter-clockwise direction as viewed in Fig. 7, the studs 70 and 72 being retracted by engaging the arcuate edge of the eaves 135. As the studs 70 and 72 register with the apertures in the projections 74, these studs are spring urged into home position where they remain until the alarm is again turned in.

From the foregoing, it appears that a person turning in the alarm cannot escape without carrying the closure cuffed to his hand unless he has a key to unlock the gripping jaws. The purpose is to have the person making the signal report to the fire department to release the closure from his arm and thereby preventing the turning in of false alarms.

Suitable inscription directing the reporter to report to a member of the fire department or any other designated individual or place for the removal of the closure from his arm is preferably printed or stamped on the closure.

The parts forming the closure are made from tool-resisting material, thereby handicapping the removal of the cuff without the use of the key.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise the preferred form of several modes of putting the invention into effect and the invention is, therefore, claimed in any of its form or modifications within the legitimate and valid scope of the appended claims.

Having thus described my invention, I claim:

1. A device for identifying the operator of mechanism mounted substantially vertical on a support comprising an enclosure for said mechanism, said enclosure having a downwardly and horizontally arranged opening through which the hand of a person may be inserted for operating said mechanism, a hand cuff having means for gripping the wrist of the operator, means in said opening and on the cuff for detachably mounting said cuff in the opening, water shedding means cooperating with the opening to prevent water accumulating between the cuff and the opening, means for releasing the cuff from its support in the opening and means operated by the operation of the mechanism for controlling the cuff gripping means and operating the cuff releasing means.

2. A device for identifying the operator of mechanism mounted substantially vertical on a support comprising an enclosure for said mechanism, said enclosure having a downwardly and horizontally arranged opening through which the hand of a person may be inserted for operating said mechanism, a hand cuff having means for gripping the wrist of the operator, means whereby said cuff is detachably mounted in said opening, water shedding means cooperating with the opening to prevent water accumulating between the cuff and the opening, means for releasing the cuff from its support in the opening and means operated by the operation of the mechanism for controlling the cuff gripping means and operating the cuff releasing means.

3. A device for identifying the operator of fire alarm mechanism mounted on a support comprising an enclosure for said mechanism having a downwardly and a substantially horizontally arranged opening through which the hand of a person may be inserted for operating said mechanism, a hand cuff including a pair of gripper jaws for engaging the wrist of the operator, means for actuating and locking said jaws in closed position, means whereby said cuff is detachably mounted in said opening, water shedding means cooperating with the opening to prevent water accumulating between the cuff and the opening, and means operating in response to said mechanism for controlling the operation of said first means and releasing the detachably mounted cuff.

4. A device for identifying the operator of a fire alarm transmitting device, including the combination with the signal transmitting device, a housing enclosing the signal transmitting device having a downwardly directed opening, a contractable hand cuff detachably mounted contiguous to said opening through which the operators hand may be inserted into said housing to operate the signal transmitting device, said housing including water shedding means for protecting the cuff from the elements, detent means for releasably supporting the hand cuff relative to the housing opening and means controlled

incident to the operation of the transmitting device for releasing the hand cuff and effecting the contraction thereof upon the arm of the operator.

- 5 5. A device for identifying the operator of a fire alarm transmitting device including a combination with the signal transmitting device, an enclosure for the signal transmitting device having a downwardly directed opening, a contractable hand cuff detachably mounted contiguous to said opening through which the operator's hand may be inserted into said enclosure to op-

erate the signal transmitting device, means for actuating and locking the hand cuff in contracted position, said enclosure including water shedding means for protecting the cuff from the elements, means for releasably supporting the hand cuff relative to the closure opening and means controlled incident to the operation of the transmitting device for releasing the hand cuff and effecting through said first means contraction thereof upon the arm of the operator.
